DESIGN FOR A LAMP

Otto E. Johnson, Chicago, Ill.

Application October 21, 1938, Serial No. 80,595

Term of patent 14 years

To all whom it may concern:

Be it known that I, Otto E. Johnson, a citizen of the United States, residing at Chicago, in the county of Cook and State of Illinois, have invented a new, original, and ornamental Design for a Lamp, of which the following is a specification, reference being had to the accompanying drawing, forming a part thereof.

The figure is a front elevational view of a lamp, showing my new design. The sides opposite to the sides disclosed are substantially plain.

I claim:

The ornamental design for a lamp, as shown and described.

OTTO E. JOHNSON.
